2 Claims. (Cl. 260—613)

This invention relates to a process for preparing a substantially quantitative yield of a mixture of more than about two parts of a 2-tertiarybutyl-4-alkoxyphenol together with one part of a 3-tertiarybutyl-4-alkoxyphenol, which process comprises reacting at an elevated temperature mono-tertiarybutyl hydroquinone with a dialkyl sulfate, an alkyl acid sulfate, an alkyl chloride, or an alkyl phosphate, said reaction being conducted in a medium comprising a non-aqueous liquid phase containing a hydrocarbon solvent or any other inert water-immiscible solvent, for example ethylene dichloride, di-isopropyl ether, di-isopropyl ketone, etc., and an aqueous liquid phase maintained in an alkaline condition during the course of the reaction.

One procedure now being used for the preparation of the two isomers of tertiarybutyl-4-alkoxyphenols involves the reaction of hydroquinone with a methylating agent to obtain 4-methoxyphenol, followed by alkylation of the latter with a source of the tertiarybutyl radical such as isobutylene or tertiarybutyl alcohol. This process and the inherent disadvantages involved are discussed in a copending application Serial No. 277,508, filed on March 19, 1952, by Young et al., entitled "Preparation of Tertiarybutyl Hydroquinone and Conversion to Isomers of Tertiarybutyl-4-Methoxyphenol," now Patent 2,722,556. In the Young et al application a new process is disclosed for the preparation of tertiarybutyl hydroquinone employing an aromatic hydrocarbon solvent to facilitate the reaction, whereby the end product consists substantially of the mono-tertiarybutyl derivative. The Young et al application also discloses a process for the preparation of a mixture of a major proportion of 2-tertiarybutyl-4-methoxyphenol and a minor proportion of 3-tertiarybutyl-4-methoxyphenol by reacting at an elevated temperature mono-tertiarybutyl hydroquinone with dimethyl sulfate, methyl acid sulfate or methyl chloride in an aqueous alkaline solution containing at least about 0.1 percent of comminuted zinc under an inert atmosphere. The process disclosed by Young et al represented a major advance over the prior art; however, as indicated in Example 6 in the Young et al. application, the product obtained represented only about a 75 percent conversion of mono-tertiarybutyl hydroquinone to mono-tertiarybutyl-4-hydroxy anisole of the following composition:

	Percent
3-tertiarybutyl-4-hydroxy anisole	79.4
2-tertiarybutyl-4-hydroxy anisole	17.6

Of the mono-tertiarybutyl hydroquinone employed by Young et al in their Example 6 as a starting material there remained in the reaction product 23.6 percent which had not entered into the reaction; in addition, a little over one percent of the starting material was converted to the dimethyl ether of mono-tertiarybutyl hydroquinone.

Although the Young et al process represents a substantial improvement over the prior art process, it is obviously more practical and economical from an operational

2

standpoint to make use of substantially all of the mono-tertiarybutyl hydroquinone employed as the starting material. In order to do so by the process disclosed by Young et al, it would be necessary to either (1) recover the unreacted material from the reaction product and employ it in a subsequent reaction or (2) employ much larger amounts of the etherification agent in which event the reaction product would contain much larger amounts of the undesirable dimethyl ether of the mono-tertiarybutyl hydroquinone.

As an unexpected improvement over the Young et al process and as a clearly marked advance over the prior art discussed in the Young et al application, I have now found that by using a solvent, such as an aliphatic or aromatic hydrocarbon, in association with the aqueous etherification medium of Young et al, that a greatly improved yield of the desired mono-tertiarybutyl-4-alkoxyphenols results. Moreover, the reaction product contains a clearly predominant proportion of the more potent antioxidant isomer 2-tertiarybutyl-4-alkoxyphenol, with a corresponding reduction in the formation of the undesirable dialkyl ether of mono-tertiarybutyl hydroquinone. Furthermore, the mono-tertiarybutyl hydroquinone starting material is substantially completely converted to form the monoethers.

An object of this invention is to provide a process for etherifying mono-tertiarybutyl hydroquinone whereby a substantially quantitative yield of monoalkyl ethers is produced. An additional object of my invention is to provide such a process wherein the ratio of 2-tertiarybutyl-4-alkoxyphenols to 3-tertiarybutyl-4-alkoxyphenols is greater than two to one. Another object is to provide a process which substantially eliminates the necessity for recovering unused starting material from the reaction mixture thereby greatly improving the economical and operational aspects of the preparation of desirable antioxidants.

In broad terms my invention provides a process for preparing a substantially quantitative yield of a mixture of more than about two parts of a 2-tertiarybutyl-4-alkoxyphenol together with one part of a 3-tertiarybutyl-4-alkoxyphenol, which process comprises reacting with agitation at an elevated temperature mono-tertiarybutyl hydroquinone with at least a stoichiometrically equivalent quantity of an etherification agent compound selected from the group consisting of dialkyl sulfates, alkyl acid sulfates and alkyl chlorides, wherein each of the alkyl groups contains from 1 to 4 carbon atoms, said reaction being conducted in the presence of a small quantity of a protective material in a medium comprising a non-aqueous liquid phase containing a solvent selected from the group consisting of aliphatic and aromatic hydrocarbons containing from about 5 to about 10 carbon atoms and an aqueous liquid phase maintained in an alkaline condition during the course of the reaction.

The temperature at which the process is conducted is advantageously from about 50° to about 150° C. More advantageously, the preferred temperature range is from about 75° to about 100° C. in which range satisfactory reaction occurs in a reasonable length of time. Still more advantageously the reaction is conducted under reflux conditions which automatically governs the temperature of the reaction depending upon the nature of the reaction medium and the concentration of reactants and reaction products therein. There is nothing critical about the temperature employed. Moreover, the reaction can be conducted under pressure if so desired; it is generally advantageously carried out at atmospheric pressure. Elevated pressures can be employed if high reaction temperatures are desired in connection with the given solvent. In conducting the reaction an atmosphere

can advantageously be employed whereby there will be insufficient oxygen to substantially oxidize the phenolic hydroxyl radicals so as to avoid any undesirable formation of by-products. Advantageously, a nitrogen atmosphere can be employed. Examples of other inert atmospheres which can be advantageously used include helium, neon, etc. However, no inert atmosphere need necessarily be employed.

Examples of etherification reagents which can be advantageously employed in accordance with the process of this invention include dialkyl sulfates, e. g. diethyl sulfate, dimethyl sulfate, ditertiarybutyl sulfate, etc., alkyl acid sulfates, e. g. propyl acid sulfate, methyl acid sulfate, etc., alkyl chlorides, e. g. isopropyl chloride, methyl chloride, secondary butyl chloride, etc. or alkyl phosphates, e. g. trimethyl phosphate, triethyl phosphate etc. Other compounds which can be advantageously employed in conducting the etherification are readily apparent. An especially advantageous etherification agent is dimethyl sulfate.

In order to produce substantially quantitative yields in accordance with the process described above, the etherification agent is advantageously employed in at least a stoichiometrically equivalent quantity in proportion to the amount of tertiarybutyl hydroquinone employed as a starting material. It has been found that larger proportions (e. g. 1.5 stoichiometrical equivalents) of the etherification agent can also be advantageously employed although there is no purpose to be achieved by using more than about twice the quantity necessary to produce mono-etherification. It has been found to be quite advantageous to employ about two thirds more of the etherification agent than is actually required on a stoichiometrical basis.

The reaction is advantageously conducted in the presence of a protective material. Most advantageously, the protective material consists of a finely divided or comminuted metal having reducing properties such as zinc or other equivalent metals. In place of zinc other protective materials can be advantageously employed, e. g. Lykopon which consists essentially of sodium hydrosulfite ($\text{Na}_2\text{S}_2\text{O}_4$). Most advantageously zinc dust can be employed. Such a protective material is advantageously employed in minute quantities. When zinc dust is employed, it has been found advantageous to use at least 0.1 percent or up to about 1% or more; generally from about $\frac{1}{4}$ to about $\frac{1}{2}$ percent of zinc dust (based on the weight of the mono-tertiarybutyl hydroquinone) can be employed whereby deleterious by-products are substantially completely eliminated. If there is a trace of residual color in the crude reaction product, removal may be made complete by distillation in the presence of about 0.1 percent zinc dust. It is evident that other metallic dusts, other powdered alkali metal hydrosulfites, and other equivalent protective materials can be similarly employed.

The non-aqueous liquid phase of the medium in which the reaction is conducted advantageously contains a solvent selected from the group consisting of aliphatic and aromatic hydrocarbons containing from about 5 to about 10 carbon atoms. Examples of such hydrocarbons include normal pentane, octane, hexane, heptane, benzene, toluene, xylene, mixtures of paraffinic hydrocarbons, straight-run naphthas and various mixtures and solvents of hydrocarbon nature derived from these materials. Other solvents can be similarly employed but those mentioned are generally most advantageously useful. A sufficient quantity of the solvent should be employed to substantially completely dissolve the mixed isomers of tertiarybutyl-4-alkoxyphenol in the reaction product. Generally speaking, about twice the weight of the mono-tertiarybutyl hydroquinone of such a solvent can be advantageously employed. Considerable variation in the amount of solvent is obviously permissible.

The amount of water employed in the aqueous liquid phase of the reaction medium is similarly subject to considerable wide variation within reasonable limits. As in-

dicated by the examples set forth below, from 4 to 5 times the weight of the mono-tertiarybutyl hydroquinone of water can be advantageously employed. These examples illustrate amounts of water and solvent which can be used satisfactorily from a practical standpoint. Variations in the amounts of water and solvent, within reasonable limits, do not deleteriously effect the efficacy of the reaction process. An important factor in conducting the process of this invention lies in providing sufficient agitation to effect thorough mixing of whatever amounts of water and solvent are used. This can be accomplished by the stirring, shaking, maintaining reflux conditions, employing other suitable means, etc.

The reaction mixture can be advantageously maintained in an alkaline condition during the course of the reaction by the incorporation of a caustic such as an alkali metal hydroxide, e. g. NaOH , KOH , etc. Advantageously, this alkaline condition is created by introducing a solution of an alkali metal hydroxide in water into the reaction mixture from time to time whereby especially high alkalinity is avoided. Undissolved caustic can also be added. By maintaining the reaction mixture in an alkaline condition, the acid resulting from the etherification reaction is neutralized. The reaction mixture is not allowed to become acidic until after the reaction has been completed.

Advantageously, enough caustic is provided in the reaction mixture so as to neutralize free acid released from the etherification agent. Too much alkalinity tends to increase the formation of the dialkyl ether of tertiarybutyl hydroquinone. Under the conditions of the reaction set forth in the examples given below, it is advantageous to limit the amount of caustic to about a 50% stoichiometrical excess of that needed to neutralize the free acid which might be formed based on the quantity of etherification agent employed, e. g. amounts in excess of 1.92 moles of caustic for each mole of dimethyl sulfate used in the examples below tended to increase the formation of dimethyl ether of mono-tertiarybutyl hydroquinone. As indicated under the reaction conditions set up in the examples, it is preferred to use the amount of caustic given in step-wise addition to the reaction mixture in order to give the most generally advantageous results. Advantageously the caustic added in aqueous solution is purged with nitrogen to remove any oxygen.

The factor of time in regard to the reaction is not critical and can be varied widely depending upon the reaction conditions. The working examples set forth below illustrate useful reaction periods under the reaction periods employed therein.

The reaction product can be separated and purified in various ways other than that illustrated by the examples which set forth an advantageous procedure found to be quite satisfactory in obtaining economical yields.

In conducting the process of this invention, it is advantageous to charge into a reaction vessel mono-tertiarybutyl hydroquinone, the protective agent such as zinc dust, water and a hydrocarbon solvent. The reaction vessel can be advantageously equipped with means for agitation, a reflux condenser, a thermometer and a dropping funnel. It is advantageous to bring the charge in the reaction vessel to a reflux condition providing constant agitation. It is then advantageous to introduce an aqueous solution of a caustic, e. g. sodium hydroxide, into the reaction vessel at such a rate that refluxing is not stopped and the reaction is maintained under alkaline conditions. After the initial introduction of the caustic, the etherification agent can be advantageously introduced over an extended period, e. g., one-half hour (longer or shorter periods can obviously be employed). During the course of the introduction of the etherification agent more caustic can be added, or additional caustic can be introduced after the etherification agent has been added. The reflux conditions are advantageously maintained with continued agitation for the remainder of the reaction period which is generally of several hours' duration. Upon a completion

of the reaction, the contents of the reaction vessel are advantageously acidified while maintaining reflux conditions; any suitable strong acid can be employed, e. g. hydrochloric acid, sulfuric acid, etc. Following this the hot non-aqueous liquid phase containing the solvent is separated from the remainder of the contents of the reaction vessel and is then advantageously washed once with water, dried under reduced pressure and the dried product advantageously purified by distillation at a reduced pressure, e. g. 10 mm. of mercury.

The following examples will serve to further illustrate this invention.

EXAMPLE 1

Materials

Monotertiarybutyl hydroquinone	83.0 gms. (0.5 mole).
Toluene	250 cc.
Dimethyl sulfate	52.5 gms. (0.416 mole).
Sodium hydroxide	32.0 gms. (0.8 mole).
Water	384 cc.
Conc. sulfuric acid	4 cc.
Zinc dust	0.5 gm.

Procedure

The mono-tertiarybutyl hydroquinone, zinc dust, toluene and 284 cc. of the water were charged to a one liter, 3-necked, round bottom flask and the mixture heated to reflux, with agitation, and refluxed for 10-15 minutes. Next, a nitrogen purged solution of 21.3 gms. of the sodium hydroxide in 100 cc. of the water was run into the refluxing mixture in 10-15 minutes; then the dimethyl sulfate was added in 30 minutes. One hour after the first of the dimethyl sulfate was added, 10.7 gms. of the sodium hydroxide was added to the reaction mixture which was then refluxed 17 hours longer with agitation. The total reaction time was 18 hours and the reaction temperature was 82-83.5° C. At the end of the reaction period, the batch was acidified with the sulfuric acid, then the hot toluene layer was separated from the aqueous layer, washed with 100 cc. of hot water, and the solvent removed by distillation at 10 mm. mercury pressure. This dried, crude material was distilled at 10 mm. mercury pressure to give a product which contained 97% mono-tertiarybutyl-4-hydroxy anisole and 3% mono-tertiarybutyl hydroquinone dimethyl ether. This mono-tertiarybutyl hydroquinone dimethyl ether was removed from the product as a low-boiler in the distillation.

Of the mono-tertiarybutyl hydroquinone charged as described in Example 1 above, 1.2% remained unreacted, 2.7% was converted to mono-tertiarybutyl hydroquinone dimethyl ether and 93.5% was converted to mono-tertiarybutyl-4-methoxyphenols of the following composition:

	Percent
3 - tertiarybutyl-4-methoxyphenol	28
2 - tertiarybutyl-4-methoxyphenol	72

EXAMPLE 2

Materials

Monotertiarybutyl hydroquinone	83.0 gms. (0.5 mole).
n-Heptane	250 cc.
Dimethyl sulfate	52.5 gms. (0.416 mole).
Sodium hydroxide	32.0 gms. (0.8 mole).
Water	384 cc.
Conc. sulfuric acid	6.8 cc.
Zinc dust	0.5 gm.

Procedure

This experiment was run exactly like the one given in Example 1 except that n-heptane was used as the solvent, the total reaction time was 14.4 hours and the reaction temperature was 78.5-79° C. The material produced analyzed 92.0% mono-tertiarybutyl-4-methoxyphenol, 6.0% mono-tertiarybutyl hydroquinone dimethyl ether and 2% mono-tertiarybutyl hydroquinone. The conversion of

mono-tertiarybutyl hydroquinone for Example 2 ran as follows:

87.5% mono-tertiarybutyl-4-methoxyphenols
5.3% mono-tertiarybutyl hydroquinone dimethyl ether
5.1% unreacted

Isomer ratio of product:

28% 3-tertiarybutyl-4-methoxyphenol
72% 2-tertiarybutyl-4-methoxyphenol

EXAMPLE 3

Materials

Monotertiarybutyl hydroquinone	83.0 gms. (0.5 mole).
Xylene	250 cc.
Dimethyl sulfate	52.5 gms. (0.416 mole).
Sodium hydroxide	32.0 gms. (0.8 mole).
Water	384 cc.
Conc. sulfuric acid	4 cc.
Zinc dust	0.5 gm.

Procedure

This experiment was run exactly like the one given in Example 1 except that xylene was used as the solvent, the total reaction time was 12.5 hours and the reaction temperature was 90.5-91.5° C. Also, instead of running under reflux during the reaction period volatile components were removed by slow distillation with replacement of the solvent as distilled. The material produced analyzed 95% mono-tertiarybutyl-4-hydroxy anisole, 4.0% mono-tertiarybutyl hydroquinone dimethyl ether and 1% mono-tertiarybutyl hydroquinone. The conversion of mono-tertiarybutyl hydroquinone for the experiment ran as follows:

89.5% mono-tertiarybutyl-4-hydroxy anisole
3.5% mono-tertiarybutyl hydroquinone dimethyl ether
3.8% unreacted

Isomer ratio of product:

28% 3-tertiarybutyl-4-methoxyphenol
72% 2-tertiarybutyl-4-methoxyphenol

It is readily apparent that other solvents, other etherification agents and other variations in materials and the various conditions can be employed to obtain results similar to those exemplified by the preceding working examples. Moreover, the process employed can be modified as may be suitable for changes in the various conditions employed. The process can be altered so as to result in the continuous etherification of mono-tertiarybutyl hydroquinone which can be introduced into the reaction zone over an extended period of time along with the introduction of the etherification agent; in such a process a portion of the non-aqueous liquid phase would be removed either continuously or from time to time after the reaction conditions had been maintained for a suitable period of time. In operating according to the continuous process, the conditions described hereinabove would be maintained by suitable addition of water, solvent, etc. as may be required from time to time.

I claim:

1. In a process for oxy-alkylating a nuclearly monoalkylated dihydric phenol to form an alkoxy nuclearly monoalkylated monohydric phenol employing a dialkyl sulfate as the oxy-alkylating agent, which process is conducted under reflux conditions and under an inert atmosphere in the absence of an alkylating catalyst, the improvement which consists of oxy-alkylating mono-tertiary butyl-hydroquinone with a stoichiometric excess of a dialkyl sulfate having from 1 to 4 carbon atoms in each alkyl radical employing a two phase alkaline reaction medium consisting of (1) an aqueous liquid phase maintained in an alkaline condition during the course of the reaction by the introduction of an alkali metal hydroxide and (2) a non-aqueous liquid phase containing a hydrocarbon selected from the group consisting of aliphatic and aromatic

hydrocarbons containing from 5 to 10 carbon atoms, whereby there is produced a substantially quantitative yield of a mixture of more than two parts of 2-tertiary-butyl-4-alkoxyphenol together with one part of 3-tertiary-butyl-4-alkoxyphenol.

2. The improvement in a process as defined in claim 1 wherein the oxy-alkylating agent is dimethyl sulfate, the

alkali metal hydroxide is sodium hydroxide and the hydrocarbon is toluene.
